JAMES R. HAMMOND, OF SEDALIA, MISSOURI.

Letters Patent No. 97,911, dated December 14, 1869.

IMPROVEMENT IN PORTABLE DERRICKS.

The Schedule referred to in these Letters Patent and making part of the same.

To all whom it may concern:

Be it known that I, JAMES R. HAMMOND, of Sedalia, in the county of Pettis, and State of Missouri, have invented a new and useful Improvement in Portable Derricks; and I do hereby declare that the following is a full, clear, and exact description thereof, which will enable others skilled in the art to make and use the same, reference being had to the accompanying drawings, forming part of this specification, in which—

Figure 1 is a top view of my improved derrick.

Figure 2 is a vertical detail section of the same, taken through the line $z z$, fig. 1.

Similar letters of reference indicate corresponding parts.

My invention has for its object to furnish an improved derrick, simple in construction, effective in operation, and easily moved from place to place, designed especially for use in connection with my improved rake, thresher, loader, and stacker, but equally applicable for other uses; and

It consists in the construction and combination of various parts of the derrick, as hereinafter more fully described.

A are the wheels of the derrick-truck, the axles B of which are made high, and are slotted longitudinally, as shown in fig. 2.

C are the bottom boards, two of which are used, and which are placed, the one directly above the other, as shown in fig. 2. The rear ends of the bottom boards C are secured, the one to the upper and the other to the lower part of the rear axle B. The forward ends of the bottom boards C are secured to bolsters, which are pivoted by a pin or king-bolt, the one to the upper and the other to the lower part of the forward axle.

D is the standard of the derrick, the lower end of which passes down through a hole in the middle part of the upper bottom board, and into the socket formed in or attached to the middle part of the lower bottom board.

E is a stand, formed by attaching an upright or post to a base-frame, said upright being made of such a height as to fit beneath the middle part of the lower bottom board C. The stand E is designed to be placed directly beneath the upright or shaft D of the derrick, to sustain the downward pressure of the weight upon said derrick.

To the upper end of the shaft D is attached a cross-arm F, which inclines slightly downward, from its centre toward its ends, as shown in fig. 2.

G is the car, to which the hoisting-apparatus is attached. The hoisting-apparatus is not shown in the drawing, as there is nothing new about its construction. The car G is provided with one or more friction-

rollers, to make it move easily, and with guards to keep it in place upon the arm F. The car G is so formed as to bear only upon its middle part and lower end, and has a shoulder upon its lower side, to fit into notches or recesses upon the upper side of the cross-arm F.

To the upper end of the car G, or to the guard-arms attached to said upper end, is attached a cord, H, which passes over a guide-pulley, h, pivoted to the side of the cross-arm F, near its middle part, so that by pulling downward upon the said rope H, the car G may be drawn inward toward the shaft D of the derrick.

To the upper end of the car G, or to one of the guard-arms attached to said upper end of the car, is attached a cord, I, which extends downward, so that by pulling upon the said cord I, the shoulder or catch of the car may be raised out of the notch or recess in the cross-arm F, so that the weight of the said car may carry it toward the end of the said cross-arm.

To the other part or end of the cross-arm F is connected a rope, J, the other end of which is attached to a small weighted truck, K, which is placed upon a double-inclined plane, L, inclining downward from each direction toward the centre, so that when the cross-arm F of the derrick has been swung to one side, to bring the load of hay over the place where it is to be deposited, and the hoisting-apparatus has been slackened, the weighted car K may draw the cross-arm F back into its proper position.

The car K may be weighted more or less, as may be desirable.

Having thus described my invention, I claim as new, and desire to secure by Letters Patent—

1. The car G and ropes H and I, in combination with the recessed inclined cross-arm F of the vertical pivoted shaft D, substantially as herein shown and described, and for the purposes set forth.

2. The double-inclined plane L, and weighted car K, in combination with the cross-arm F of the vertical shaft D of the derrick, substantially as herein shown and described, and for the purpose set forth.

3. An improved portable derrick, formed by the combination of the truck A B C, stand E, shaft D, cross-arm F, car, G, ropes H I, rope J, weighted car K, and double-inclined plane L, with each other, substantially as herein shown and described, and for the purpose set forth.

JAMES R. HAMMOND.
